UNITED STATES PATENT OFFICE.

JOHN M. DEAN, OF LOWELL, MASSACHUSETTS.

WIRE-CUTTING MACHINE.

No. 839,121.

Specification of Letters Patent.

Patented Dec. 25, 1906.

Application filed May 10, 1906. Serial No. 316,151.

To all whom it may concern:

Be it known that I, JOHN M. DEAN, a citizen of the United States, residing at Lowell, in the county of Middlesex and State of Massachusetts, have invented certain new and useful Improvements in Wire-Cutting Machines, of which the following is a specification.

My invention relates to machines for cutting wire rods, and more particularly to machines for cutting the pointed ends from wires to form the points of graphophone-machines, and also to form hackle-pins, card-pins, gill-pins, and comb-pins used in textile machinery.

The objects of my invention are to so cut such points or pins that they shall be of a uniform length and so that their butt-ends shall be smooth and shall be squarely at right angles to their length.

In the drawings, Figure 1 is an enlarged detail view of the point-guide and cutters on the line X X of Fig. 5 from the back. Fig. 2 is end view of my machine, showing in different sections portions of the different parts. Fig. 3 is a general front view. Fig. 4 is a top view of one end of the machine. Fig. 5 is an enlarged sectional view showing portions of the cutters, feed-rolls, and guides.

In this machine, the stock to be operated on consists of straight wires pointed at one or at both ends.

My machine consists of the frame or table A, which supports two arches B B. The main shaft C, which is given motion by any suitable means, is supported by adjustable bearings D D, carried by arches B B. Shaft C carries a gear E, a cutter F, and feed-rolls G and H. The counter-shaft K is also carried by suitable adjustable bearings supported by table A. One of these bearings is shown at J and the other is similar thereto, but is under saddle R. Counter-shaft K carries a gear L, which meshes with and receives motion from gear E. Shaft K also carries a cutter M.

The shaft C is not directly over shaft K, but is behind and parallel with it. This is to aid the stock by the force of gravity in descending to the cutting-point and to prevent it from being forced out by the cutters instead of being cut by them. The bearings of shafts C and K are adjustable in line with each other.

The cutters F and M consist of metal disks

rigidly secured to their respective shafts. Their rims are beveled on the sides opposite from each other. Their adjoining faces are in the same plane, and their rims touch or slightly pass each other.

The feed-rollers G and H are provided with rims of rubber or other elastic material and are of the same diameter as cutter F. Roller G is fixed on shaft C; but roller H is made so that it can be moved along shaft C to accommodate different lengths of stock, and it can be secured in place by set-screw 6. The wires N are fed to the machine by being placed in suitable quantities upon the parallel feed-guides 11 and 12. These feed-guides 11 and 12 taper toward the end nearest the feed-rollers G and H and are bent at right angles at their outer ends. They are supported by means of angle-irons 13 and 14. Each angle-iron has a vertical slot 15, and through said slots and guides 11 and 12 are passed, respectively, bolts 27 and 26, whereby guides 11 and 12 may be raised or lowered and may be held in place by tightening said bolts. Angle-iron 14 is fixed to base-plate P, which in turn is fixed to table A. Angle-iron 13, however, can be slid along base-plate P and may be held in place thereon by tightening the nut of bolt 29, whose shank passes through slot 18 in base-plate P. The head of bolt 29 extends on both sides of slot 18 under base-plate P. Feed-guides 11 and 12 may thus be raised or lowered and the distance between them varied to accommodate wires of different diameters and lengths.

Feed-guides 11 and 12 taper toward the feed-rollers, as stated, and rest against the slanting surface of saddle R, which is firmly fixed to table A. The top part of this saddle R is made of metal and at the part 16 is curved to conform to the surfaces of feed-rollers G and H. It is between this surface 16 of saddle R and rollers G and H that rods N pass in being cut. Guides 11 and 12 are so adjusted as to leave a portion 17 of saddle R above their ends. This is to prevent the wires N from passing through the cutters in any except in positions parallel with shafts C and K, as they might do did they not first strike a parallel guiding-surface, such as 17.

Saddle R does not extend beyond cutters F and M, and consequently the points 7 cut from wires N fall between the side of saddle R and guide S into a chute T, by which they

are conducted to suitable receptacles. The remaining portions of wires N are carried along by feed-rollers G and H past saddle R, when they are released and roll down the 5 slant 19 to the level portion 20 of the tray B, so placed and made as to receive them.

I also use an end guide or gage S, which consists of a flat piece of metal of suitable shape set parallel with cutters F and M and 10 supported by a horizontal screw-threaded shank 22, passed through a hole in arch B. It can be moved to and from the cutters and revolved on shank 22, and it can be held in any position by means of adjusting-nuts 21, 15 carried by shank 22. This guide S is intended to gage the lengths of the pins or points 7 which are to be cut from wires N, as it is parallel to cutters F and M and can be moved toward or from them. The pointed ends of 20 wires N are automatically kept in contact with guide S by having the whole machine arranged so that it is higher at the side opposite to the side at which are the cutters and this guide S, as see Fig. 3. This tends to 25 make all the wires N keep evenly in contact with guide S, as the jarring of the machine causes them to slide in that direction until their points touch it lightly.

In order to support the ends of points 7 30 while wires N are passing through the cutters and are actually being cut and so that they may be cut squarely and cleanly, I form a projection 41 at the end of guide S. This projection 41 is at the part 42 concave in 35 shape, as shown in Fig. 1, to conform to the contour of the curved part 16 of saddle R. Guide S is so set by rotating it upon shank 22 as to bring the curved part 42 of projection 41 a distance a trifle less than the radius of 40 one wire N above the curved part 16 of saddle R. Projection 41 of guide S extends almost or quite to a point opposite the point of contact of cutters F and M. By the use of 45 this point-guide 41 the tips of the points 7 of wires N are supported during the period when wires N are being cut at nearly their extreme tips, and as the bodies of said wires are also firmly held between saddle R and rollers G and H the cut is clean and at right angles 50 to the axis of the wires. End guide S stops and is continued by guide 41 at the point where the cutters begin to cut. Were it not for point-guide 41 the cut would be likely to be diagonal.

55 To make the space between saddle R and rollers G and H conform to the diameters of different wires which it is desired to cut, I carry shafts C and K in adjustable bearings. The bearings at one end of these shafts are 60 shown in detail in Figs. 2 and 4 at D and J. Bearing D is carried by arch B and consists of slanting guides 32 integral with said arch and the box 33. Adjusting-bolts 31 and 31 at top and bottom allow the box 33 to be 65 moved back and forth and to be adjusted

with delicacy and when adjusted to be held firmly in place. Bearing J consists of slanting guides 36 in line with guides 32, carried by table A and box 37. Adjusting-bolts 35 and 35 at top and bottom allow this bearing 70 to be adjusted in a similar manner to bearing D. By making bearings D and J adjustable I can take up or allow for any wear on cutters F and M.

The advantages of my invention are speed 75 in operation, accuracy in cutting, and adjustability.

What I claim as my invention, and desire to cover by Letters Patent, is—

1. In a wire-cutting machine, lower adjustable bearings, upper adjustable bearings in line therewith, parallel shafts carried thereby, coöperating rotary cutters carried by said shafts, guide-rollers carried by the upper of said shafts, a guide-saddle coöperating therewith, feed-guides, and an end guide as described. 80

2. In a wire-cutting machine, lower slanting adjustable bearings, upper slanting adjustable bearings in line therewith but not 90 perpendicular above them, parallel shafts carried thereby, coöperating rotary cutters carried by said shafts, guide-rollers carried by the upper of said shafts, a guide-saddle coöperating therewith, feed-guides, and an 95 end guide as described.

3. In a wire-cutting machine, downwardly-inclined parallel shafts, feed-rollers carried by the upper of said shafts, a guide-saddle and feed-guides inclined correspondingly 100 with said shafts, coöperating rotary cutters carried near the lower ends of said shafts, and an end guide parallel with and outside of said cutters.

4. In a wire-cutting machine, a driving-shaft, a guide-roller fixed thereon, a guide-roller slidably adjustable thereon, a rotary cutter fixed thereon, a lower shaft parallel with said driving-shaft, and a rotary cutter fixed thereon, combined with slanting feed-guides, a feed-guide saddle which projects above the lower ends of said feed-guides and comprises a surface adjoining the guide-rolls which is concaved to correspond with their rims, and an end guide as described. 105

5. In a wire-cutting machine, coöperating rotary cutters, a guide-saddle, coöperating guide-rollers, adjustable feed-guides, and an adjustable end guide as described. 110

6. In a wire-cutting machine, coöperating rotary cutters, a guide-saddle, coöperating guide-rollers, adjustable feed-guides, and an end guide capable of lateral adjustment and comprising a point-guide adapted to support the points of the wires while being cut. 115

7. In a wire-cutting machine, lower adjustable bearings, upper adjustable bearings in line therewith, parallel shafts carried thereby, coöperating rotary cutters carried by said shafts, a guide-roller fixed to the upper 120

shaft, and a guide-roller slidably adjustable along said upper shaft, combined with inclined adjustable feed-guides, a fixed guide-saddle which projects above the lower ends 5 of said feed-guides and comprises a surface adjoining the guide-rollers which is concaved to correspond with their rims, and an end guide capable of lateral adjustment and comprising a point-guide adapted to support the

points of the wires while being cut, as described.

In testimony whereof I affix my signature in presence of two witnesses.

JOHN M. DEAN.
